SUITCASE

Franz Schwennicke, Brussels, Belgium

Application October 17, 1951, Serial No. 16,969

Term of patent 14 years

(Cl. D87—5)

To all whom it may concern:

Be it known that I, Franz Schwennicke, a citizen of the Kingdom of Belgium and residing at 14, rue Notre Dame du Sommeil, Brussels, Belgium, have invented a new, original, and ornamental Design for a Suitcase, of which the following is a specification, reference being made to the accompanying drawing, forming part thereof:

Fig. 1 is a perspective view of a suitcase, showing my new design in open position;

Fig. 2 is a perspective view from another angle of the suitcase of Fig. 1;

Fig. 3 is a sectional view of the front part of the suitcase of Fig. 1, showing the handle therefor.

The sides of the design not shown are substantially plain.

I claim:

The ornamental design for a suitcase, substantially as shown and described.
